(57) **CLAIM**

The ornamental design for a video camera, as shown and described.

DESCRIPTION

FIG. 1 is a front and left side perspective view of a video camera according to the present invention;

FIG. 2 is a rear and left side perspective view of the video camera of FIG. 1;

FIG. 3 is a rear and right side perspective view of the video camera of FIG. 1;

FIG. 4 is a left side elevational view of the video camera of FIG. 1;

FIG. 5 is a right side elevational view of the video camera of FIG. 1;

FIG. 6 is a top plan view of the video camera of FIG. 1;

FIG. 7 is a bottom plan view of the video camera of FIG. 1;

FIG. 8 is a rear elevational view of the video camera of FIG. 1; and,

FIG. 9 is a front elevational view of the video camera of FIG. 1.

The portions of the video camera in broken lines are shown for illustrative purposes only and form no part of the claimed design.
